CLAIM

The ornamental design for an electrotransport drug delivery system, as shown and described.

DESCRIPTION

FIG. 1 is a top perspective view of an electrotransport drug delivery system, showing one embodiment of our new design;

FIG. 2 is a top plan view thereof;

FIG. 3 is a bottom plan view thereof;

FIG. 4 is an end elevational view thereof; and

FIG. 5 is a side elevational view thereof, the opposite side elevation is a mirror image thereto;

FIG. 6 is a top perspective view of an electrotransport drug delivery system, showing a second embodiment of our new design;

FIG. 7 is a top plan view thereof;

FIG. 8 is a bottom plan view thereof;

FIG. 9 is an end elevational view thereof; and,

FIG. 10 is a side elevaton of FIG. 6, the opposite side elevation is a mirror image thereto.
